UNITED STATES PATENT OFFICE.

CHARLES V. D'OSSONE, OF PHILADELPHIA, PENNSYLVANIA.

HAIR-ROLL.

SPECIFICATION forming part of Letters Patent No. 787,903, dated April 25, 1905.

Application filed June 15, 1904. Serial No. 212,638.

To all whom it may concern:

Be it known that I, CHARLES V. D'OSSONE, a citizen of the United States, residing in the city and county of Philadelphia, in the State of Pennsylvania, have invented certain new and useful Improvements in Hair-Rolls, of which the following is a full, clear, and exact description, reference being had to the accompanying drawings, of which—

10 Figure 1 is a front elevation showing the preferred form of the invention. Fig. 2 is a transverse vertical section of Fig. 1. Fig. 3 is a view similar to Fig. 2, but showing a modified form of the invention. Fig. 4 is a section 15 on line 4-4, Fig. 3.

This invention relates to that kind of supports or rolls for ladies' hair sometimes termed "rats," which are formed of fine elastic wire braided into tubular form, the wire at the ends 20 of the tube being bunched together and firmly secured. Usually the roll is covered by a netting of cotton thread or the like, which is secured at the ends. Heretofore these rolls were liable when worn to become displaced.

25 The main object of my present invention is to provide a simple means whereby the roll may be secured in proper position to the hair of the wearer.

Referring to the drawings, *a* is a roll made 30 of a piece of braided wire of tubular form, the free ends *a'* being flattened and the wires bunched together and bent over upon themselves in the usual way.

I insert in and through the flattened ends 35 of the roll two eyelets *b*, Fig. 2, the proper distance apart to receive the shanks of an ordinary hair-pin *c*.

In using the device the roll is applied to the head of the wearer in the usual way, the hair 40 being combed back over the roll, and the latter is secured to the hair by passing the shanks of the hair-pin *c* through the eyelets *b* into the hair and thrusting the free ends of the hair-pin through interstices between the wires into 45 the interior of the tube, as shown. Thus the roll will be securely held in place, and the

points of the pin, being protected, cannot come against the scalp of the wearer. When, which is commonly the case, the roll is covered with tubular netting *d*, the ends of the netting may 50 be bent over upon the flattened ends of the wire fabric and the eyelets passed through it, the netting, as well as the wire, and clenched on the opposite side, thus securely holding said ends of the netting, as shown. 55

Instead of two eyelets there may be used but a single one at each end, in which case a suitable pin would be used in lieu of a double shank or hair-pin for securing the roll to the hair. 60

Instead of using ordinary eyelets I sometimes employ the construction illustrated in Figs. 3 and 4. This consists in what may be termed a "staple-eyelet," formed of an ordinary wire staple *e*, which is forced through 65 the flattened end of the roll *a* and the ends of the shanks turned over, so as to form eyes *f* for the passage of the shanks of a hair-pin *c*, as shown in said figures.

Having thus described my invention, I claim 70 as new and desire to secure by Letters Patent—

1. A tubular braided-wire hair-roll, having its free ends flattened and having eyelets secured to and passing transversely through said ends respectively, adapted to receive a pin for 75 securing the roll to the hair, substantially as and for the purpose specified.

2. A tubular, braided-wire hair-roll, having its free ends flattened, and having a tubular net covering, and having eyelets secured to 80 and passing transversely through said ends respectively and through said covering, whereby said covering is fastened to said ends, substantially as and for the purpose set forth.

In testimony whereof I have hereunto affixed my signature this 23d day of May, A. D. 1904.

CHARLES V. D'OSSONE.
